RULER

Arthur Kuechenmeister, St. Louis, Mo.

Application July 28, 1933, Serial No. 682,700

9 Claims. (Cl. 33—107)

This invention relates to rulers. The term "ruler" is used herein in a general sense to include straight-edges, scales, T-squares, and analogous drawing, cutting or scribing instruments used by 5 draftsmen, architects, engineers and students.

Rulers now on the market and commonly used are of two general classes; firstly, those made of wood, or of wood with celluloid (pyroxylin) edges, and secondly, those made of metal. Wood 10 by nature being hygroscopic is readily affected by atmospheric changes and caused to warp, curl, bend or bow, and splinter. Therefore rulers of the first class, wholly or partly of wood, true on leaving the shop, are likely soon to become 15 untrue. Retruing being an expensive procedure, it is cheaper and more expedient to replace an "off true" ruler than to attempt to retrue it. Rulers having blades of wood, or of wood with celluloid edges, are unsatisfactory for the further 20 reason that when of long lengths it is necessary to build up the wood of laminations, cross grained in relation to each other, in an effort to prevent or minimize warping. This results in wood of such thickness as to necessitate beveling the edge 25 or edges to enable the user to work close to the drawing surface, whether said edges are of wood in the all wood type, or of celluloid in the wood with celluloid edge type. On the other hand, if the wooden center portion is made sufficiently 30 thin to obviate the necessity of beveling the edge or edges, then said center portion warps laterally, giving the ruler a lateral spring or spread which results in distorting drawn lines from parallelism. Rulers of the second class, that is all metal 35 rulers, now in commercial use are not satisfactory because they mar or stain the paper, rust and pit, and are much more expensive than wooden rulers because of the higher cost of metal and also because, after milling, the edges must 40 be trued by grinding with an abrasive such as a carborundum wheel, this being an expensive operation which must be performed slowly to avoid overheating the metal. For such reasons few metal rulers are used as compared to rulers 45 of wood, or of wood and celluloid.

The main object realized by the present invention is the provision of an inexpensive ruler which avoids the defects and objectionable characteristics of the aforesaid two classes of rulers now commonly used and which is of such durability that it can safely be guaranteed to remain true. Still other objects and advantages realized, some 50 of which are specifically set forth hereafter, will 55 be readily understood by reference to the several

embodiments of the invention illustrated in the accompanying drawing, wherein—

Fig. 1 is a perspective view partly in transverse section;

Figs. 2, 3, 4, 5, 6 and 7 are transverse sectional views through one side only of the ruler, showing variations of construction; and

Figs. 8, 9 and 10 are transverse sectional views showing still other variations or modifications of construction.

The rulers shown in the drawing each comprises a body of sheet metal having attached thereto one or two ruling edges of celluloid. The term celluloid is used in a general sense to include equivalent and preferably transparent materials, such as bakelite. The sheet metal is preferably light in weight and non-corrosive, such as aluminium, stainless steel, Allegheny metal, brass, German silver, etc.

The ruler illustrated in Fig. 1 comprises a 20 sheet metal body portion 20 and two celluloid ruling edges 21 and 22. The body portion has three longitudinally extending upwardly opening parallel corrugations 23, which give added 25 rigidity to the ruler, provide grooves in which to lay pencils, pens or other drawing instruments, and also serve as guides to the fingers, as in drawing long straight lines. Along both edges of the body portion 20 the sheet metal thereof is bent over and under at 24 in a horizontal direction, thence downward at 25 in a vertical direction, and thence outward and slightly upward at 26, thus forming outwardly opening channels or 30 grooves for receiving the celluloid ruling edges and also adding rigidity to the ruler. Each ruling 35 edge 21 and 22 has a longitudinally extending shallow concave groove or depression 27 in its bottom face near the inner edge thereof. Each ruling edge is inserted in its corresponding channel of the body portion and pressure is then applied to compress and close the sheet metal walls of the channel into secure gripping engagement with the ruling edge, the part 26 of the channel wall being forced into the shallow groove 27, all as shown in Fig. 1. The ruling edges 21 and 22 40 are thus permanently secured or joined to the body portion 20. The bend of the metal between the walls 25 and 26 of each channel, forms a smooth, narrow, convex, metallic, bearing surface 28 which engages the paper and supports the 45 ruling edges (in fact the entire ruler) slightly elevated from the drawing surface.

These surfaces 28, extending the entire length of the ruler, constitute "runners" by which the 50 ruler "rides" on, and minimize frictional engage- 55

ment with, the drawing surface. Furthermore, the slight elevation of the bottom surfaces of the celluloid drawing edges above the drawing surface by said runners 28, minimizes the chances of 5 blotting or smearing said drawing surface, especially when the ruler is moved away from a freshly drawn inked line. There is the further important advantage that the slight elevation of the bottom surfaces of the celluloid members 10 out of contact with the drawing surface avoids scratching or chafing of said bottom surfaces and thus preserves the transparency of the ruling edges.

The construction illustrated in Fig. 2 is similar 15 to that shown in Fig. 1, except that the wall 24 of the channel is longer, the wall 26 bows away from the bottom surface of the ruling edge 21 and constitutes a slightly wider runner 28 which by its engagement with the paper supports said 20 ruling edge at a somewhat higher elevation from the paper, and only the extreme edge of the wall 26 engages in a narrow groove 27 in the bottom surface of the ruling edge.

The construction of Fig. 3 is similar to that of 25 Fig. 2, except that the wall 26 is not bowed away from and is parallel to the under surface of the ruling edge, thus forming a flat surfaced runner 28 for engaging the surface of the paper and elevating the ruling edge from the drawing surface less than in Fig. 2.

The construction of Fig. 4 is similar to that of 30 Fig. 3, except that the wall 26 inclines upwardly into interlocking engagement with an angular groove in the under surface of the ruling edge 21. 35 Here, as in Fig. 1, there is a narrow smooth convex bearing surface or runner 28 for engagement with the paper and slightly elevating the ruling edge from the drawing surface.

In the construction of Fig. 5 there is no groove 40 in the bottom surface of the ruling edge 21 engaged by the wall 26 and rivets 29 are provided as an additional means of securing the ruling edge 21 in the channel at the edge of sheet metal body portion 20. In this instance the flat bottom surface 45 of the wall 26 constitutes the runner 28 for engaging the drawing surface.

Fig. 6 illustrates a construction similar to that of 50 Fig. 5, except that the walls 24, 25 and 26 are not integral with the body portion 20, but are formed from a separate strip of sheet metal.

The construction of Fig. 7 is similar to that of 55 Fig. 3, except that the wall 26 is at a higher elevation than the bottom surface of the ruling edge 21 and the latter surface bears directly upon the drawing surface. In this instance no metal touches the drawing surface.

The construction illustrated in Fig. 8 is the same as that shown in Fig. 2, except that additional 60 rigidity is furnished by a sheet metal arch member 30, underlying the body portion 20, and sprung or snapped into place with its upstanding edges 31, 31 closely engaging and interlocking with the walls 25, 25 respectively of the channels for the two ruling edges 21 and 22.

65 Another variation of the construction is shown in Fig. 9, wherein the body portion 20 is formed of two sheets of metal placed face to face and brazed, welded or soldered together except at their edges, where the wall 24 of each channel is formed by the upper sheet, and the walls 25 and 26 of each channel are formed from the lower sheet. Otherwise the construction is similar to that shown in Fig. 2.

Still another variation of construction shown in 70 Fig. 10 is similar to that of Fig. 9, except that the

walls 25, 26 of the channels in which the ruling edges 21 and 22 are secured, are formed from strips of sheet metal secured to the underside of the body portion 20 by rivets 33.

The celluloid members 21 and 22 may, or may 5 not, as preferred, each have a beveled surface 35 adjacent its instrument guiding edge, as shown at the right in Figs. 1 and 8.

As thus appears, rulers embodying the present 10 invention do not require the use of cement or adhesive to secure the celluloid ruling edges to the sheet metal body portion. So far as known, the only successful adhesive for securing together celluloid and metal is "liquid celluloid", which is celluloid dissolved in acetone or some other solvent. 15 When such "liquid celluloid" is so employed, the solvent present attacks and softens the celluloid. To re-harden the celluloid it must be "aged" or "cured" from thirty to ninety days. Furthermore, where this adhesive comes into contact with 20 the celluloid, the finish and polish of the latter is destroyed, making re-polishing necessary. All of these difficulties are eliminated by the construction of the present invention.

Furthermore, rulers embodying the present 25 invention are not entirely dependent for rigidity upon the natural stiffness of the sheet metal middle portion, added rigidity being imparted thereto by the open box-beam effect resulting from the metal walls of the channels which receive the 30 celluloid ruling edges, and, if desired, by corrugating the sheet metal middle portion. In this manner sufficient rigidity may be obtained while using thin light-weight sheet metal.

The feature of the relatively narrow metallic 35 surfaces or runners which contact the drawing surface is also highly advantageous in minimizing friction and preserving the transparency of the celluloid ruling edges by slightly elevating the 40 same out of contact with the drawing surface and thereby avoiding scratching or chafing of the bottom surfaces of said celluloid members. The elevation of said celluloid edges slightly above the work or drawing surface also prevents ink from collecting in the angle formed by the drawing 45 edges and the drawing surface.

What is claimed is:

1. In a ruler, a body portion having a channel along one side thereof, both said body portion and the wall of said channel being of sheet metal, and a non-metallic ruling edge having a part 50 thereof along one side located in said channel, the top, bottom and end portions of the wall of said channel being compressed into fixed engagement with corresponding portions of the surface of the enclosed part of said ruling edge, thereby forming a permanent and immovable joint between said body portion and ruling edge.

2. In a ruler, a body portion having a channel along one side thereof, both said body portion and the wall of said channel being of sheet metal, and a non-metallic ruling edge having a part 60 thereof along one side located in said channel and a longitudinally extending groove in said part, the top, bottom and end portions of the wall of said 65 channel being compressed into fixed engagement with corresponding portions of the surface of the enclosed part of said ruling edge and into said longitudinal groove of the enclosed part, thereby forming a permanent and immovable joint between said body portion and ruling edge.

3. A ruler comprising a body portion having a channel along each side thereof, said body portion and the wall of each channel being of sheet metal; and two non-metallic ruling edges each having a 70 75

part thereof along one side located in one of said channels, the top, bottom and end portions of the wall of each channel being compressed into fixed engagement with corresponding portions of the surface of the part of the ruling edge which it encloses, thereby forming a permanent and immovable joint between said body portion and ruling edges.

4. In a ruler, a body portion having a channel along one side thereof, both said body portion and the wall of said channel being of sheet metal; and a non-metallic ruling edge having a portion thereof along one side located in said channel, with a portion of the wall of the channel projecting below the bottom surface of the ruling edge and constituting a "runner" for engaging the drawing surface and elevating said ruling edge clear thereof.

5. In a ruler, a body portion having a channel along one side thereof, both said body portion and the wall of said channel being integrally formed from a single piece of sheet metal; and a non-metallic ruling edge having a portion thereof along one side located in said channel, with a portion of the wall of the channel projecting below the bottom surface of the ruling edge and constituting a "runner" for engaging the drawing surface and elevating said ruling edge clear thereof.

6. In a ruler, a body portion having a channel along one side thereof, both said body portion and the wall of said channel being of sheet metal; and

a non-metallic ruling edge having a portion thereof along one side located in said channel, with a portion of the wall of the channel projecting below the bottom surface of the ruling edge and having a curved surface constituting a "runner" for engaging the drawing surface and elevating said ruling edge clear thereof.

5

7. A ruler comprising an elongated sheet metal body portion having a channel along each side thereof and one or more longitudinal corrugations between said channels each corrugation forming an upwardly opening groove; and two non-metallic drawing edges permanently secured in said channels respectively.

8. A ruler comprising a body portion having a channel along each side thereof, both said body portion and the wall of each channel being of sheet metal; and two non-metallic ruling edges each having a portion thereof located in one of said channels, the wall of each channel having a portion extending below the bottom surface of said ruling edge and constituting a runner for engaging the drawing surface.

9. A ruler comprising a body portion of sheet metal having a channel portion along each side edge thereof; non-metallic ruling edges secured in said channel portions respectively; and a reinforcing sheet metal arch member positioned beneath said body portion and between said channel portions.
